BENJAMIN E. GETCHELL, OF PLAINVILLE, CONNECTICUT, ASSIGNOR TO THE TRUMBULL ELECTRIC MFG. CO., OF PLAINVILLE, CONNECTICUT, A CORPORATION OF CONNECTICUT.

QUICK-BREAK SWITCH MECHANISM.

1,418,558.

Specification of Letters Patent. Patented June 6, 1922.

Application filed April 26, 1920. Serial No. 376,803.

To all whom it may concern:

Be it known that I, BENJAMIN E. GETCHELL, a citizen of the United States of America, residing at Plainville, Connecticut, have invented a new and useful Quick-Break Switch Mechanism, of which the following is a specification.

My invention relates particularly to enclosed switch mechanism in which the circuit is adapted to be closed by hand and opened by hand. It will be obvious, however, that the invention in its broadest aspect is not limited to an enclosed switch. I also have designed the mechanism with the intention that the circuit may be opened automatically, but this aspect of the invention is more fully developed in my application #376,804.

The main object of the invention claimed herein is to provide a rugged and reliable mechanism which may be operated to close the circuit by hand by the single throw of a handle and to insure an automatic quick break entirely beyond the control of the operator when the handle has been started toward the open circuit position.

Another object is to arrange the mechanism so as to provide a maximum leverage in opening and closing the switch, so that a comparatively light spring may be employed for operating the switch without requiring an excessive force for the hand operations.

Fig. 1 is a front view of the parts of an enclosed type of switch embodying the improvements of my invention, the parts being shown in the closed circuit position.

Fig. 2 is a vertical section and side view looking from the left of Fig. 1.

Fig. 3 is a similar view showing the parts in the open circuit position.

Fig. 4 is a view on a larger scale showing the parts in the position which they would occupy when opening the circuit by hand at the instant when the automatic release has taken place and while the handle is still held by the operator and showing the automatic low voltage or under voltage release in the position it would occupy with the current still on.

Fig. 5 is a perspective view on a larger scale showing parts of the release mechanism.

The box or receptacle 10 constitutes the support for all of the mechanism. In the form shown, the switch is provided with

three blades such as 11, each of which is pivoted to a post 12 and adapted to engage a spring clip 13. These parts are supported on an insulating base 14 as is customary. It will be obvious that the number of switch blades and contacts is immaterial to this invention. The blades are all connected by an insulating cross piece 15.

The operating handle 16 has a hub 17 mounted in one wall of the receptacle 10, which hub extends through into the inside of the receptacle for connection to the switch blades. On the inside of the receptacle is a U-shaped crank 18 having one end connected to the hub 17 and the other end pivoted in a support 19. The cross bar 20 has its ends pivoted at 20' in the walls of the receptacle. This cross bar is connected by one or more links 21 to the cross bar 15. The crank 18 is connected to the cross bar 20 by means of a hinged link consisting of the bars 23 and 24 which are pivoted together at 25. A spring 26 is connected at one end to a lug 27 in the receptacle and at the other end to a screw 28 in the bar 24. The bar 24 is preferably double, one part being on each side of the upper end of the bar 23. Between the two sides of the upper end of the bar 24 is pivoted a latch 29 on the cross bar 20. This latch has a shoulder 30 which is normally engaged by the tip 31 on the upper end of the bar 23 when the parts are in the positions shown in Figs. 2 and 3. In this position the two bars 23 and 24 act as if they were in one piece, the spring 26 pulling downward with the pivot center 25 in the back of or to the left, as viewed in Figs. 2 and 3, of the center line between the cross bar 20 and the cross piece of the crank 18 so that the tension on the spring is trying all the time to pull the pivot 25 to the right, as viewed in Figs. 2 and 3, or forward, which movement is normally prevented by the engagement of the tip 31 with the shoulder 30 on the latch 29.

When the operator starts to open the switch the outward swinging of the handle swings the crank 18 and the lower end of the folding link outwardly and downwardly. When the handle and crank reach the position shown in Fig. 4, the rear end of the tip 32 of the latch 29 engages the trip catch 33, which holds it up while the folding link continues to move downwardly and the tip 31 is released from the catch shoulder 30.

This occurs before the switch blade 11 leaves the contact 13 and the spring 26 immediately pulls the parts downwardly with a quick break action into the position shown in Fig. 5 4 opening the circuit at a maximum speed. When the handle 16 is released, from the position shown in Fig. 4 it will be noted that the spring 26 is pulling against the bar 24 and the hinge 25 and thus pulling the bar 23 10 downwardly and imparting a rotative movement to the crank 18 and the attached handle to return the handle to its normal open circuit position as shown in Fig. 3. In returning to this position it will be noted that 15 the tip 31 is reengaged with the catch shoulder 30. For this purpose the rear approach to the shoulder 30 is preferably inclined as shown.

The latch 29 is recessed at the upper portion as shown at 39 and a pin 38 is secured 20 in the bar 24 and fits in said recess. This construction provides for a limited movement of the latch, the edges of the recess at the extreme limits of movement of the latch 25 abutting against said pin 38. The latch 29 may be enlarged as shown at 39 to provide an abutment for the upper end of the bar 23 in one direction.

It will be seen that the bars 23 and 24 30 constitute a hinge which is normally rigid for moving the switch but when the latch is moved the rigidity of the hinge is broken. Other arrangements of latch 29 will be obvious to those skilled in the art.

35 It will be noted that I have also provided an electro-magnetic trip consisting of a magnet 35, an armature 36 and a member 37 adapted to engage the front end of the latch member 29 when the electro-magnet 40 is deenergized. This construction is claimed in another application.

I claim:

1. In a quick break switch mechanism, a 45 pivoted switch blade, a pivoted crank, a bar pivoted to swing on a radius materially greater than the length of said crank arm, a connection between said bar and said switch blade, a hinge connection between said bar and said crank, a spring connected to 50 said hinge connection, a latch for said hinge connection and means for releasing said latch.

2. A quick break switch construction comprising, a hinged switch blade, an operating 55 crank, a link connecting said crank and said blade, a pivoted handle, a hinged member connecting said handle and said crank, a latch for connecting the parts of said hinged member together to enable the handle to 60 close the switch, a spring tending to open the switch, and means for releasing said latch and permitting said spring to open the switch with a snap action.

3. In a switch, a movable switch contact, 65 a box containing said contact, an external

handle pivoted in one side of said box, a crank on the inside of said box secured to the hub of said handle, a second crank longer than the first pivoted in said box and connected to said contact, a hinged member 70 connecting said cranks, and a latch carried by one of said cranks and normally connecting the parts of said hinged member, a spring connected to said hinged member, and means for releasing said latch. 75

4. In a switch, two swinging members, one of which is longer than the other, a contact connected to the longer member, a handle connected to the shorter member, a hinged member connecting said swinging members, 80 a latch connecting the parts of said hinged member, a spring connected to one part of said hinged member, and means for releasing said latch.

5. In a switch, two swinging members, 85 one of which is longer than the other, a contact connected to the longer member, a handle connected to the shorter member, a hinged member connecting said swinging members, a latch connecting the parts of 90 said hinged member, a spring connected to one part of said hinged member, and means for releasing said latch automatically when the handle is moved to open the circuit.

6. In a switch, two swinging members, one 95 of which is longer than the other, a contact connected to the longer member, a handle connected to the shorter member, a hinged member connecting said swinging members, a latch connecting the parts of 100 said hinged member, a spring connected to one part of said hinged member, and means for releasing said latch automatically when the handle is moved to open the circuit, and means for releasing said latch independently of the 105 movement of the said handle.

7. In a switch, a hinged contact blade, a swinging member connected thereto, an operating crank, a hinged member connecting said crank and said swinging member, a 110 latch carried by said swinging member normally interlocking the parts of said hinged member, a spring for moving said parts to open the circuit when said latch is released, and means for releasing said latch. 115

8. In a switch, a hinged contact blade, a contact for said blade, a relatively long crank, a link connecting said crank and blade, a relatively short crank and a member permanently connecting said cranks 120 whereby when the short crank is moved the long crank and link will move said blade with a toggle action.

9. In a switch, a hinged contact blade pivoted on one center, a relatively long crank 125 pivoted on a different center, a link connecting said crank and blade, a relatively short crank pivoted on a center different from the others and a member connecting said cranks whereby when said cranks are 130

- 5 moved the blade will be moved by a toggle action.
10. In a switch, a hinged contact blade, a relatively long crank pivoted to one side of the pivot point of said blade, a relatively shorter crank pivoted below the pivot point of said blade, a connection between said long crank and blade and a member connecting said cranks whereby when the cranks are 10 moved the blade will be moved by a toggle action.
11. In a switch, a switch blade, an operating crank, a normally rigid hinged member connecting said blade and crank whereby 15 when the crank is manipulated the switch will be opened or closed and means for breaking the rigidity of said hinge member when the opening movement of the switch is initiated.
12. In a switch, a switch blade, an operating crank, a normally rigid hinge member connecting said blade and crank whereby when the crank is manipulated the switch will be opened or closed, means for breaking 20 the rigidity of said hinge member when the opening movement of the switch is initiated and means for opening said switch with a snap action after the rigidity of the hinge member has been broken.
13. In a switch, a switch blade, an operating crank, a hinge connection between said crank and said switch blade, a latch for holding said hinge connection in one position, means for releasing said latch, a spring 25 for opening said switch with a snap action after said latch is released and for returning said crank to the normal open switch position.
14. In a switch, a switch blade, an operating crank, a handle connected to said crank, a hinge connection between said crank and said switch blade, a latch for holding said hinge connection in one position, means for releasing said latch, a spring for opening 30 said switch with a snap action after said latch is released and for returning said crank and handle to the normal open switch position.
15. In a switch, a switch blade, an operating crank, a normally rigid hinge member connecting said blade and crank whereby when the crank is manipulated the switch will be opened or closed, means for breaking the rigidity of said hinge member when the 35 opening movement of the switch is initiated and means for opening said switch with a snap action after the rigidity of the hinge member has been broken and for returning the operating crank to the normal open switch position.
16. In a switch, a switch blade, an operating crank, a handle connected to said crank, a normally rigid hinge member connecting said blade and crank whereby when 40 the crank is manipulated the switch will be
- opened or closed, means for breaking the rigidity of said hinge member when the opening movement of the switch is initiated and means for opening said switch with a snap action after the rigidity of the hinge member has been broken and for returning the operating crank and handle to the normal open switch position.
17. In an electric switch, a hinged switch blade, a crank hinged adjacent thereto and adapted to stand substantially at right angles thereto when the switch blade begins to contact and connected to said switch blade, an operating crank, and a member, connecting said operating crank and said first-mentioned crank, said operating crank being substantially parallel with said switch blade when said switch blade is in a closed circuit position, whereby a powerful toggle action is produced during the latter portion of the closing movement of the switch member.
18. In an electric switch, a stationary contact, a hinged switch member adapted to engage said contact, a crank hinged adjacent said switch member, a link connecting said crank and said switch member and standing substantially at right angles to said switch member when said switch member begins to engage said contact, an operating crank, and a member connecting said operating crank and said first-mentioned crank, said operating crank extending substantially parallel with said connecting member when said switch member is in the closed circuit position, whereby a powerful toggle action is produced during the latter portion of the closing movement of the switch member.
19. In an electric switch, a stationary contact, a hinged switch member adapted to engage therewith, a crank connected to said hinged switch member at an acute angle when the hinged switch member is adjacent the stationary contact, an operating crank, and a member connecting said operating crank and said first-mentioned crank, said operating crank being substantially at right angles to said connecting member when the hinged switch member begins to engage said stationary contact, whereby a powerful toggle action is produced during the latter portion of the closing movement of the switch member.
20. In an electric switch, a movable member, a latch pivoted thereto, a hand operable crank, a bar connected to said crank and normally engaging said latch, a second bar hinged to said first bar and to said movable member, means for releasing said latch from said first bar, and a spring connected to said second bar for moving said movable member when said latch is released and automatically re-engaging the said first bar with said latch.

BENJAMIN E. GETCHELL.
